HEAT EXCHANGE ELEMENTS
Hatsuo Kawano, 16 3-chome, Kitaizuocho,
Taisho-ku, Osaka, Japan
Filed Sept. 15, 1959, Ser. No. 849,131
3 Claims. (Cl. 165—182)

This invention relates to heat exchange elements for air coolers, air heaters, oil coolers, oil heaters and the like.

The object of the present invention is to provide means to increase the thermal efficiency and strength.

With this object in view, the present invention provides a heat exchange element, wherein a number of fins and spacers having a pair of wings are alternately inserted on a fin-tube and then the fin-tube is expanded to secure firmly the fins and spacers by forcing a die of slightly greater outer diameter than the inner diameter of the fin-tube therein. A pair of projections are formed opposite to each other at outer portions of each surface of each fin, and each wing of the spacers is fitted between each pair of projections.

According to the present invention, not only the fins are firmly secured to their accurate positions, but also they are supported firmly by means of the wings of the spacers. Therefore, comparatively thin fins being able to be used, the material can be saved as well as the heating or cooling efficiency can be increased. Moreover, the fin-tube being expanded by forcing a die therein after the fins and spacers are inserted, the assembly is very easy.

Other and the further objects of the present invention will become apparent from the following specification and claims taken together with the accompanying drawings in which is shown the preferred embodiment of the heat exchange element according to the present invention.

FIG. 1 is a perspective view of a material of spacers according to the present invention.

FIG. 2 is a perspective view of a fin, a spacer and a fin-tube according to the present invention.

FIG. 3 is a sectional elevation showing assembly of a heat exchange element according to the present invention.

FIG. 4 is a sectional elevation of a heat exchange element embodying the present invention.

FIG. 5 is a sectional elevation taken on the line 5—5 of FIG. 4.

FIG. 6 is an elevation of a part of a modified heat exchange element embodying the present invention.

FIG. 7 is a perspective view of a fin and spacer of FIG. 6.

As shown in FIG. 1, a number of aluminium spacers 11 provided with a pair of wings 12 are made by cutting off a tube 13 along the lines 14 successively. A pair of projections 15 adapted for insertion of the wing 12 therebetween are pressed out opposite to each other at the outer portions of each surface of each aluminium fin 16. A number of the fins 16 and the spacers 11 are loosely inserted alternately on a copper fin-tube 18 fitting the wings 12 between the projections 15 respectively, and then a die 19 of slightly greater outer diameter than the inner diameter of the fin-tube 18 is forced therein. Thus the fin-tube 18 is expanded to secure firmly the fins 16 and the spacers 11.

2

FIGS. 6 and 7 show a modified heat exchange element in which the fins 16 and the spacers 11 provided with two elongated holes 16₁ and 11₁ respectively are alternately inserted on two fin-tubes 18.

It is thought that the invention and its advantages will be understood from the foregoing description and it is apparent that various changes may be made in the forms, construction and arrangement of the parts without departing from the spirit and scope of the invention or sacrificing its material advantages, the form hereinbefore described and illustrated in the drawings being merely a preferred embodiment thereof.

Having thus described my invention, what I claim and desire to secure by Letters Patent of the United States is:

1. A heat exchange element comprising, in combination, a tube for conducting a heat transfer medium, a plurality of fins along said tube spaced from each other and each consisting of a substantially flat plate having at least one aperture therein through which said tube passes and having spaced projections thereon, and spacers between said fins and spacing them from each other, each spacer consisting of at least one ring fitting around said tube and a plurality of radially outwardly extending tabs on said ring having a radial dimension substantially equal to the radial dimension of said plates and having a dimension parallel to the axis of said tube substantially equal to the axial dimension of said ring, said tabs fitting between and being retained by said projections on said plates.

2. A heat exchange element as claimed in claim 1 in which said spacers each have two diametrically opposed tabs projecting therefrom and said aperture in said plate is centrally located therein.

3. A heat exchange element comprising, in combination, a plurality of tubes for conducting a heat transfer medium, a plurality of fins along said tubes spaced from each other and each consisting of a substantially flat plate having a plurality of apertures therein through which said tubes pass, and spacers between said fins and spacing them from each other, each spacer consisting of a plurality of rings fitting around said tubes and a plurality of radially outwardly extending tabs on said rings, said tabs having a dimension parallel to the axis of said tubes substantially equal to the axial dimension of said rings, there being at least one tab on each ring projecting toward the next adjacent ring and being joined to the tab on said next adjacent ring which projects toward said each ring, and the remaining tabs on said rings having a dimension on the radial direction thereof sufficient to bring said tabs to the edges of said plates.
